Letters Patent No. 2149 - Dated - Aug. 1. 1865.

Design for a Bass-relief bust of Mr. Lincoln.

the schedules referred to in these Letters Patent and making part of the same.

To all whom it may concern:

Be it known that I, Elizabeth T. Bunting, of Philadelphia, County of Philadelphia State of Pennsylvania, have invented or produced a new and original design for a bass-relief bust of Abraham Lincoln; and I do hereby declare the accompanying Drawing, with the following explanation of the same, to form a full, clear and exact description of the said Design.

The figure in the accompanying drawing represents in bass-relief, a bust of Abraham Lincoln.

I claim

The design for a bass-relief bust of Abraham Lincoln substantially as shown in the accompanying drawing.

In testimony whereof I have signed my name to this specification in the presence of two subscribing witnesses.
